BUFFING WHEEL

William Ruthven, Oak Park, Ill., assignor to Ajax
Buff Company, Chicago, Ill., a corporation of
Illinois

Application February 5, 1951, Serial No. 209,385

8 Claims. (Cl. 51—193)

1

This invention relates to a buffing wheel, and more particularly to a buffing wheel provided with improved structure for pumping cooling air past the buff to cool the same and the surface of the workpiece being operated on.

A buffing wheel normally comprises an annular cloth buff attached to a hub which is, in turn, attached to a rotatable mandrel or shaft. Normally, a plurality of such wheels are attached to the shaft in axially abutting relation in order to obtain a substantial area of buffing wheel contact with the workpiece. It will be appreciated that the quality of work performed by such a buffing wheel assembly and the speed with which the work can be performed are dependent upon the surface characteristics of the buff and the speed of rotation of the buffing assembly. Both the speed of rotation and the surface abrasiveness of the wheel are limited because of the heat that is generated by friction and the consequent tendency toward burning of the cloth buff or discoloration of the workpiece.

The buffing wheels of the present invention are provided with dual cooling means in the form of radial cooling passages between adjacent wheels of a buffing wheel assembly and with cooling air pumping structure including vanes or fan blades, thus providing forced air cooling of the buffs through the radial cooling air passages. The pumping vanes are of improved and simplified construction, embodied in a separately formed vane ring, which is assembled with the buffing wheel in an expeditious manner.

It is, therefore, an object of the present invention to provide a simplified and improved buffing wheel.

Another object of the invention is to provide an improved buffing wheel having dual means for directing cooling air past the cloth buff.

A further object of the invention is to provide an economically formed buffing wheel including simplified means for axially spacing adjacent abutting wheels of a buffing wheel assembly to provide radial cooling air passages and including expeditiously formed cooling air pumping structure.

Still another object of the present invention is to provide a simplified and improved cooling air pumping structure for a buffing wheel including expeditious means for attaching the vane structure to the wheel.

Other objects, features and advantages of the present invention will be apparent from the following detailed description of one preferred embodiment, by way of example only, taken in conjunction with the accompanying drawings.

2

On the drawings

Figure 1 is a side elevational view of a buffing wheel according to the present invention;

Figure 2 is an enlarged, fragmentary partially sectional view of a buffing wheel assembly and including two such wheels as shown in Figure 1; and

Figure 3 is an enlarged, diametral sectional view of the cooling vane ring of the buffing wheel shown in Figure 1.

As shown on the drawings:

As shown in Figure 1, a buffing wheel 10 has an annular cloth buff 11 attached to a hub structure 12. The cloth buff 11 may be of any satisfactory construction, such as a plurality of radially pleated bias-cut cloth strips which are assembled in laminated fashion and sewed together. The resultant buff 11 has a rounded, generally circular inner periphery 14 defined by the closed loops of the cloth strips and has a generally circular outer or working periphery 15.

In order to fixedly attach the cloth buff 11 at its inner peripheral portion to the hub assembly 12, a clamping disk 16, of generally flat configuration, is provided with a central aperture 17 defined by an integral axially extending annular hub flange 18 for receiving a rotatable shaft or mandrel 19 (Figure 2) which is, in turn, attached to power means (not shown) for rotating the wheel or a plurality of wheels at a desired angular speed. The disk 16 is formed with a plurality of integral spaced projections or clamping teeth 20 formed at the outer periphery of the disk and extending in the same axial direction as the flange 18. The distal end portions of the teeth 20 are tapered to form sharp terminal points 21.

In assembling the disk 16 with the buff 11, the teeth 20 are driven through the inner peripheral portion of the buff. The end portions of the teeth 20 extending through the buff 11 are received in respective receiving slots or apertures 22 of an annular clamping ring 24. These free end portions of the teeth 20 are bent radially inwardly to lie against the axially outward surface of the clamping ring 24 to form locking tab portions 25 for fixedly retaining the buff 11 between the clamping ring 24 and the disk 16.

As seen in Figures 1 and 2, a plurality of radially extending cooling air channels or passages 26 are formed between adjacent locking tab portions 25 of the teeth 20. Means are provided for increasing the depth of the cooling air channels or passages 26. Herein, such means comprise respective protuberances or embossments 27, which are embossed or impressed axial-

ly outwardly in the metal of the ring 24 under the respective locking tabs 25. Thus, the resultant cooling air passages 26 are of a width equal to the thickness of the locking tabs 25 plus the axial height of the embossments 27.

As seen in Figure 2, a plurality of buffing wheels 10 (herein shown as two in number) are abutted axially and retained between a pair of clamping plates 28 and 29 having respective central apertures 30 and 31 receiving the mandrel 19. For stability purposes, the clamping plate 29 has its aperture 31 defined by an annular, axially extending integral flange 32 with the end of the flange 32 abutting the end of the clamping disk flange 18. Thus, the two buffing wheels 10 and the two clamping plates 28 and 29 comprise a buffing wheel assembly 34 which is retained on the mandrel 19 by an annular shoulder 35 formed thereon at one side of the assembly 34 and a nut 36 threadedly inserted over a threaded end portion 37 of the mandrel 19 and abutting the other side of the buffing assembly 34.

For providing an air flow path through the clamping plates 28 and 29, respective angularly spaced apertures 38 and 39 are formed therethrough. To form air flow paths through each of the disks 16, a plurality of angularly spaced apertures 40, herein shown as four, are formed therethrough. It will thus be seen that rotation of the buffing assembly 34 will induce a centrifugal force on the air contained therein to produce a radially outwardly directed cooling air stream through the cooling air passages 26 with the air entering the assembly through the plate apertures 38 and 39 and the disk apertures 40.

According to the concepts of the present invention, improved cooling air pumping means are provided. In the present instance such means comprise a cooling air pumping structure or vane ring 41 of generally annular construction. The pumping ring 41 has a plurality of radially spaced integral fan blades or pumping vanes 42 struck from a substantially frusto-conical surface portion 43. The vanes 42 are generally triangular in configuration and are slanted or angularly formed in a uniform direction with respect to the frusto-conical surface 43.

For fixedly attaching the pumping ring 41 to the disk 16 of a buffing wheel 10, an integral radially inwardly extending annular flange 45 is formed on the ring and abutted against the axially inward surface of the disk 16 in coaxial relation thereto. Respective projections or tabs 46, formed in an axially inwardly extending direction from the outward defining edge portions of each of the disk apertures 40, are received in mating notches or cut-outs 47 formed in the inwardly peripheral portion of the flange 45. The free ends of the tabs 46 are then bent radially outwardly to lie against the surface of the flange 45 to fixedly interlock the vane structure 41 to the disk 16.

It will be readily seen that rotation of the buffing assembly 34 will induce an axial movement of air into the interior of the assembly due to the fan or pumping action of the vanes 42 which are disposed in slanted or acute angularly disposed relation relative to the plane of rotation of the buffing assembly. Therefore, a sufficient supply of cooling air will be drawn into the buffing assembly 34. In addition, the rotating vanes 42 will assist in inducing a centrifugal force on the incoming air for augmenting the

radially outwardly directed movement of the cooling air by pumping the air through the radial cooling air channels 26 to cool the buffs 11 of both of the wheels 10 and to cool a workpiece.

From the above discussion, it will be understood that the present invention provides an improved buffing wheel having dual means for inducing cooling air flow past the cloth buff to cool the buff and the workpiece. The dual cooling air inducing means includes an improved and simplified pumping vane structure which is formed separately and fixedly assembled to the wheel during final assembly in an expeditious manner.

It will be understood that modifications and variations may be effected without departing from the scope of the novel concepts of the present invention.

I claim as my invention:

1. A buffing wheel comprising a cloth buff, clamping members at least one of which has axial air passages therethrough fixedly secured to said buff on opposite sides thereof, and cooling air pumping structure fixedly attached in coaxial relation to one of said clamping members, said structure including an integral attachment portion abutting said one clamping member, an integral substantially frusto-conical portion, and integral cooling air directing vanes extending from the plane of said frusto-conical portion for pumping air axially through said passages and radially outwardly to cool said cloth buff.

2. A buffing wheel comprising an annular cloth buff, a clamping disk having integral peripherally spaced teeth extending through said buff, an annular ring abutting the opposite side of said buff and having apertures for receiving the free end portions of said teeth, said teeth free end portions being deformed radially of said ring to lie against the outward surface thereof to clamp said ring and said disk to said buff, said deformed portions of said teeth forming radial cooling air channels therebetween, and cooling air pumping structure fixedly attached to said disk, said structure including integral spaced vanes formed in slanted relation at acute angles to the plane of rotation of said wheel for inducing axial air flow toward said wheel and radial cooling air flow past said wheel through said cooling air channels.

3. A buffing wheel comprising an annular cloth buff, a clamping disk having integral peripherally spaced teeth extending through said buff, an annular ring abutting the opposite side of said buff and having apertures for receiving the free end portions of said teeth, said teeth free end portions being deformed radially of said ring to lie against the outward surface thereof to clamp said ring and said disk to said buff, said deformed portions of said teeth forming radial cooling air channels therebetween, and cooling air pumping structure fixedly attached to said clamping disk, said structure including an integral attachment portion abutting said disk, an integral annular substantially frusto-conical portion, and integral cooling air directing vanes extending from the plane of said frusto-conical portion in slanted relation at acute angles to the plane of rotation of said wheel for inducing axial air flow toward said wheel and radial cooling air flow past said wheel through said cooling air channels.

4. In a buffing wheel assembly including a plurality of buffing wheels disposed in coaxial abutted relation with radially extending cooling

air passages formed between the respective wheels and axial air passages passing through said wheels, means for pumping air into said assembly through said axial air passages and radially outwardly of said assembly through said radial passages, said pumping means comprising respective annular vane rings having integral annular flanges fixedly attached to the respective wheels, each of said rings having an integral annular substantially frusto-conical portion extending radially outwardly and axially inwardly with respect to the respective wheels, and integral cooling air directing vanes formed in spaced relation in said frusto-conical portion and extending at acute angles relative thereto.

5. In a buffering wheel including a clamping disk and a clamping ring fixedly disposed against respective opposite sides of an annular cloth buff and with a plurality of tabs lying against the axially outward surface of said ring and forming radial cooling air channels therebetween, separate cooling air pumping structure comprising an integral annular radially inwardly directed flange portion having a plurality of radially inwardly facing notches therein, said disk having a plurality of integral tabs engaged in said notches and having end portions overlying said flange to fixedly secure said pumping structure to said disk, an integral annular frusto-conical portion of said structure extending radially outwardly and axially inwardly of said wheel, and a plurality of integral cooling air directing vanes formed in said frusto-conical portion in slanted relation thereto, said vanes inducing axial flow of air toward said wheel and radial flow of air past said wheel through said cooling air channels.

6. A buffering wheel comprising an annular cloth buff, a substantially plane circular disk abutting one side surface of said buff, teeth formed integrally with said disk and extending through said buff, an annular ring abutting the opposite side of said buff and having peripheral apertures formed therein to receive said teeth and local embossments adjacent each of said apertures, said teeth having tab portions deformed radially to overlie said embossments and to secure said disk and said ring to said buff, said teeth and said embossments projecting beyond said ring to

space the associated wheel from an adjacent wheel of a buffering assembly, and cooling air pumping structure fixedly attached in coaxial relation to said disk, said structure including an integral attachment portion abutting said disk, an integral annular substantially frusto-conical portion, and spaced integral cooling air directing vanes extending at acute angles from the plane of said frusto-conical portion.

10. 7. In a buffering wheel, a separate cooling air pumping structure comprising an annular frusto-conical portion, a plurality of cooling air directing vanes formed on said frusto-conical portion in slanted relation thereto, and an annular 15 radially inwardly directed attachment flange secured to said frusto-conical portion, said flange having means for attaching to the buffering wheel and an aperture adjacent the center of said attachment flange for the passage of cooling air 20 to the buffering wheel.

8. In a buffering wheel having a clamping disc and a clamping ring fixedly disposed on respective opposite sides of an annular cloth buff, a cooling air pumping structure comprising an integral annular attachment flange abutting said disc and having a plurality of notches therein, said disc having integral tabs received in said respective notches and having end portions deformed radially of said disc to overlie said annular flange to fixedly attach said flange to said disc on one side thereof, and a plurality of spaced integral cooling air-directing vanes formed on said flange at acute angles to the plane of rotation of said buffering wheel, said vanes lying wholly on the other side of said flange from the disc to which said flange is attached.

WILLIAM RUTHVEN.
